UNITED STATES PATENT OFFICE.

LYMAN B. SMITH, OF CHELSEA, MASSACHUSETTS.

CUT-OFF FOR HOSE-NOZZLES.

SPECIFICATION forming part of Letters Patent No. 310,326, dated January 6, 1885.

Application filed February 21, 1884. (No model.)

To all whom it may concern:

Be it known that I, LYMAN B. SMITH, a citizen of the United States, residing at Chelsea, in the county of Suffolk and State of Massachusetts, have invented certain new and useful Improvements in Cut-Offs for Hose-Nozzles; and I do hereby declare that the same are fully described in the following specification, and illustrated in the accompanying drawings.

10 The object of this invention is to provide a simpler and more effective cut-off for hose-nozzles, faucets, and the like than has heretofore been known, and at the same time to regulate the size of the opening without forming 15 angular crevices or destroying the rotundity of the stream.

My invention consists in a nozzle or faucet having in a suitable chamber a single sliding plate perforated at one side of its center, so as 20 to coincide and be thrown out of coincidence with the tubular water-way, and recessed to receive the pins which move it when the nozzle is partially rotated.

In the drawings, Figure 1 is a longitudinal 25 section showing the end of a pipe to which the nozzle is attached, and my improved cut-off in position to stop the flow. Fig. 2 shows the valve or cut-off detached, and Figs. 3 and 4 its two extreme positions, dotted lines denoting the intermediate point.

The pipe A has a terminal cap, B, with an axial perforation, C, and a fixed projecting pin, D, in its plane outer face, E. From this face an annular flange, F, projects to form the 30 cylindrical wall of the cut-off chamber.

G is the valve or cut-off, an elliptical metal plate lying in this chamber flat against the face E. Its water-way is a single perforation

or recess, H, at one side of the center. It has also two recesses, I I, one of which receives 40 the pivotal pin D, fixed to the chamber, and the other receives a like pin, K, projecting from the smooth disk or collar L, which forms the inner end of the nozzle N, and the remaining wall of the chamber. A coupling, O, 45 encloses the collar L, and, screwing upon the threaded exterior F of the chamber, secures the nozzle to the pipe A. A packing-ring, P, between the collar and the coupling, prevents leakage. When the nozzle is partially rotated, the pin K in its collar L carries the 50 valve G, with which it engages, from side to side of the chamber, opening and closing the passage alternately by about a quarter-turn of the nozzle.

I claim as my invention—
1. In a hose-nozzle or faucet, a cut-off consisting of a single perforated sliding plate held between parallel walls, and movable laterally between them by a partial rotation of the nozzle or cap, for the purpose set forth.

2. The cap B, having a plane outer face with a central perforation, a projecting pin, and a threaded annular flange, and the nozzle N, with its plane collar and projecting pin, in 60 combination with the recessed sliding cut-off G and an annular coupling holding said flange and collar in contact with the cut-off, substantially as set forth.

In testimony whereof I hereto affix my signature in presence of two witnesses.

LYMAN B. SMITH.
